UNITED STATES PATENT OFFICE.

CLINTON D. TABOR, OF HUNTINGTON, NEW YORK, ASSIGNOR OF ONE-HALF TO
HERMAN I. SORENSEN, OF NEW YORK, N. Y.

ELEVATING PIVOT FIXTURE.

Application filed April 24, 1920. Serial No. 376,391.

To all whom it may concern:

Be it known that I, CLINTON D. TABOR, a citizen of the United States, residing at Huntington, in the county of Suffolk and State of New York, have invented new and useful Improvements in Elevating Pivot Fixtures, of which the following is a specification.

This invention relates to an elevating pivot fixture which is more particularly designed for use on windows in which the sash is moved vertically for interlocking the same with and unlocking the same from the sill or stool of the frame and also rotating said sash about a vertical axis for opening and closing the same.

The objects of this invention are to provide a fixture of this character which is simple in construction, easily assembled and also dismembered, not liable to get out of order and contains few parts which are arranged compactly and require less cutting away of the wooden sashes and frames for mounting the fixture on the window.

In the accompanying drawings: Figure 1 is a fragmentary inside elevation of a window frame and sash equipped with my improved elevating pivot fixture. Figures 2 and 3 are vertical longitudinal sections taken on line 2—3, Fig. 6, looking outwardly and inwardly, respectively. Figure 4 is a horizontal section taken on line 4—4, Fig. 3. Figures 5, 6 and 7 are vertical sections taken on the correspondingly numbered lines in Figs. 2 and 4. Figures 8, 9, 10, 11, 12, 13 and 14 are detached perspective views of different parts of the elevating pivot fixture.

Similar characters of reference indicate corresponding parts throughout the several views.

20 represents the lower horizontal sill or stool of the window frame and 21 the lower horizontal bar of the sash which are adapted to be interlocked with and also unlocked from each other upon moving the sash vertically, this locking effect being attained by a longitudinal rib 22 arranged on the upper side of the sill and engaging with a longitudinal groove 23 on the underside of said sash bar.

Within a recess 24 in the top of the sill is arranged a sill plate 25 which may be secured thereto by screws 26. On its upper side this sill plate is provided with a rib 27

which forms a continuation of the rib on the sill. On the underside of the lower sash bar the same is provided with a sash plate preferably made of front and rear sections 28, 82 having a groove 29 on its underside 60 which is in line with the sash bar groove 23 and which receives the rib of the sill plate when the sash is parallel with the frame and lowered. On its front edge the front section 28 of the sash plate is provided with an upwardly-projecting face plate 30 which may be secured to the lower sash bar by screws 31. Above the sash plate and behind the face plate the lower sash bar is provided with a recess 32 which receives part 70 of the means for raising and lowering the sash and pivotally connecting the same with the frame, said means being constructed as follows:

33 represents a vertical pivot circular one-piece pin journaled in a bearing 34 in the sill plate and connected at its upper end with an upright guide block or standard 35 having a downwardly facing shoulder 36 which engages with the upper side of the 80 sill plate. This pivot pin is held against upward movement by providing the lower part of the pivot pin with an annular groove forming an upwardly-facing annular shoulder 37 thereon and providing the underside 85 of the sill plate with one or more retaining lips 38 which are arranged around the pivot pin and engage their lower ends with said shoulder, as shown in Figs. 2 and 6.

Prior to assembling the sill and sash plates, the retaining lips 38 are left apart, as shown in Fig. 14, to permit the pivot pin 33 to be introduced into the bearing 34 from the upper end of the latter until the upper shoulder 36 engages with the upper end of 95 the bearing and the lower shoulder 37 is arranged below the bearing, after which the lips are bent inwardly by a suitable tool until their lower ends engage with the lower shoulder which faces the bearing, thereby 100 securely coupling the sill and sash plates against disengagement without employing any separate parts which would involve possible loss and increased cost.

The pivot pin 33 and guide block 35 are 105 so mounted on the sash that the latter is capable of rising and falling independently of the pivot pin and guide block but these parts are compelled to turn together. For this purpose the sash plate is preferably 110

divided into front and rear longitudinal sections 28, 82, which are arranged side by side and two bosses 40, 41 are formed on the upper sides of these sash plate sections, respectively, which have their opposing sides constructed to form between them a guideway 42 of rectangular form in horizontal section which slidingly receives the guide block 35 of corresponding rectangular form 10 in horizontal section. The two sash plate sections and guide bosses are detachably connected with each other by screws 43 arranged in said bosses, as shown in Figs. 3 and 4.

15 Means are mounted on the face plate of the sill plate which are operatively connected with the guide block for raising and lowering the sash relatively to the sill of the frame. The means for this purpose shown 20 in the drawings, are constructed as follows:

39 represents a circular bearing formed in the rear face of the front boss 40 with its axis arranged horizontally and transversely of the sash plate and 44 an opening arranged 25 axially in line with said bearing and in the bottom thereof which is formed by the face plate 30. Within this bearing 39 is journaled a rotary tumbler 45 the inner or rear face of which is preferably flush with the 30 rear face of the boss 40 while its front face engages the bottom of the bearing 39 and is provided with a hub 46 which projects forwardly through the face plate opening 44. The tumbler is turned by means of a crank, 35 lever or handle 47 arranged in the front of the face plate 30 and provided with a rearwardly projecting square shank 48 at its inner end which is secured axially in a correspondingly-shaped opening 49 in the 40 tumbler by a radial coupling pin 50. For the purpose of enabling this device to be built compactly and still enable the pin 50 to be applied to the tumbler and crank for connecting the same as well as dismembering 45 the same when required, the central part of the rear side of the tumbler is left full, as shown at 51, to provide the necessary stock in which to form the openings 52 for the coupling pin 50, but those parts of the rear 50 side of the tumbler extending from the openings 52 to the periphery of the tumbler are cut away, as shown at 53, to form recesses or passages through which the coupling pin is passed when inserting or removing the 55 same. For a similar reason the lower part of the front boss 40 and the adjacent inner edge of the front sill plate section are cut away to form a recess 54 through which the coupling pin 50 may be passed when assembling or dismembering the parts.

60 The tumbler and the guide block are operatively connected so that upon rocking the tumbler the sash will rise and fall. The improved means for this purpose comprise a 65 shuttle block 55 which reciprocates in a

horizontal groove 56 formed in the upper part of the front side of the guide block, and is eccentrically connected with the tumbler by means of a circular crank pin 57 engaging a circular opening 58 in the rear side of 70 the tumbler on one side of its center and provided with a reduced shank 59 which is riveted in an opening in the shuttle block.

Upon turning the tumbler by means of the 75 crank handle, the crank pin 57 moves the shuttle block bodily and thereby causes the sash and associated parts to rise or fall on account of the thrust exerted by the shuttle block on the guide block, as the former slides in the groove of the latter.

80 By this means motion is transmitted to the sash for raising or lowering the same with a minimum of friction and in such manner that the sash can be operated easily and with a practically uniform action 85 throughout the entire range of throw of the hand lever.

I claim as my invention:

1. A pivot fixture for windows comprising a one piece bearing, and a pivot pin 90 provided at one end with a wide part turning in contact with the bore of said bearing and an enlarged shoulder engaging said bearing adjacent one end of said bore, while the other end of said pin is provided with 95 a narrow part and a second shoulder which faces toward said enlarged shoulder, and said bearing being provided at the other end of said bore with an integral lip which engages the second shoulder.

100 2. A pivot fixture for windows comprising a one piece bearing, and a pivot pin provided at one end with a wide part turning in contact with the bore of said bearing and an enlarged shoulder engaging said bearing adjacent one end of said bore, while the other end of said pin is provided with a narrow part and a second shoulder which faces toward said enlarged shoulder, and said bearing being provided at the other 105 end of said bore with an integral lip which engages the second shoulder and with said narrow part of the pin.

110 3. A pivot fixture comprising a sill plate adapted to be attached to a sill and provided with a bearing, a sash plate adapted to be secured to a sash and divided into sections which have bosses adapted to form between them a guideway when said sections are placed together, and a pivot pin turning in 115 said bearing and having a guide block which slides in said guideway but is compelled to turn therewith.

120 4. A pivot fixture comprising a sill plate adapted to be attached to a sill and provided with a bearing, a sash plate adapted to be secured to a sash and divided into sections which have bosses adapted to form between them a guideway when said sections are placed together, a pivot pin turning in said 125 130

- bearing and having a guide block which slides in said guideway but is compelled to turn therewith, screws connecting said bosses, and means mounted on said sash plate 5 and operatively connected with said guide block for raising and lowering the sash relatively to the sill.
5. A pivot fixture comprising a sill plate, a sash plate, a pivot rotatable on the sill plate and slidable on the sash plate, a rotary tumbler operatively connected with said pivot and provided with a central opening, a bearing on said sash plate for said tumbler, a crank provided with a rearwardly projecting shank disposed in said opening, said tumbler being provided with transverse openings communicating with said central opening and with radial recesses extending to the periphery of the tumbler, and a coupling pin inserted through said recesses and openings and securing the tumbler to said shank.
- 10 15 20 25 30 35 40 45 50 55 60 65
6. A pivot fixture comprising a sill plate, a sash plate, a pivot rotatable on the sill plate and slidable on the sash plate, a rotary tumbler operatively connected with said pivot and provided with a central opening, a bearing on said sash plate for said tumbler, a crank provided with a rearwardly projecting shank disposed in said opening, said tumbler being provided with transverse openings communicating with said central opening and with radial recesses extending to the periph-
- ery of the tumbler, and a coupling pin inserted through said recesses and openings and securing the tumbler to said shank and said sash plate being provided with a recess which is adapted to register with the recesses in said tumbler and provide a passage 40 for said coupling pin.
7. A pivot fixture comprising a sill plate provided with a vertical bearing, a sash plate provided with a horizontal bearing, an upright pivot pin journaled in the bearing of the sill plate and provided with a block which is guided on the sash plate and provided with a horizontal groove, a rocking tumbler journaled in the bearing of the sash plate, a shuttle block sliding in said groove and pivotally connected with said tumbler on one side of the axis of the latter and means for rocking the tumbler.
8. A pivot fixture comprising a sill plate provided with a vertical bearing, a sash plate provided with a horizontal bearing, an upright pivot pin journaled in the bearing of the sill plate and provided with a block which is guided on the sash plate and provided with a horizontal groove, a rocking tumbler journaled in the bearing of the sash plate, a shuttle block sliding in said groove, a pin mounted on said shuttle block and engaging with a pivot recess formed on said tumbler on one side of the axis of the latter and means for rocking the tumbler.

CLINTON D. TABOR.
